CLOCK SETTING MECHANISM AND CIRCUIT

Henry Maerz, Brooklyn, N. Y., assignor to Self Winding Clock Company, Inc., Brooklyn, N. Y., a corporation of Delaware

Application February 20, 1948, Serial No. 9,737

5 Claims. (Cl. 58—24)

1

This invention relates to clock setting mechanism and circuits which, though of more general utility, are especially useful for simultaneously and automatically setting all the clocks in a secondary clock system.

As conducive to a clear understanding of the invention, it is noted that in a system in which a number of clocks are actuated from a master clock that sends out impulses at predetermined time intervals, where frequent and simultaneous resetting of all such clocks is required, as for example on ships, trains, planes or the like that travel over great distances and therefore cross many time zones, it would be burdensome so frequently to reset the secondary clocks.

Where push button means is provided at the master clock to reset the secondary clocks, it is a rather time consuming and tiring procedure manually to operate such push button for the many quickly repeated operations required for the transmission of the numerous impulses needed to advance the clocks a full hour and it is much more arduous to effect the advance of eleven hours required to retard the clocks by one hour.

In systems in which the secondary clocks move in half minute steps, in some cases it would require 60 depressions and in other cases 120 depressions of the push button to effect the necessary 120 impulses to advance the clocks one hour and 660 or 1320 such depressions respectively to move the clocks ahead eleven hours.

Moreover, in such manual resetting operation, superlative care is required to operate the push button properly, for if the depressions are too short, some of the secondary clocks may receive too few impulses due to the voltage drop along the line and if the depressions are not sufficiently positive, too many impulses which may be unequal in duration may be transmitted and in both cases the indicated time on the various clocks would differ.

Where the secondary clocks are stopped one hour instead of rotating them forward eleven hours, when it is desired to retard the clocks one hour, they must all be started immediately on the hour in order that they indicate the correct time thereafter. This is difficult to accomplish with precision by manual control and even where automatic restarting means for the secondary clocks is provided at the end of the hour period, in both cases they will all show the incorrect time for one full hour without any indication that they are kept stationary for resetting purposes.

Where the master clock is provided with mech-

2

anism whereby it may be synchronized by a signal from a remote source and the master clock in turn sends a correction impulse to the secondary clocks, say fifteen minutes after impression upon the master clock, the secondary clocks will of course not be corrected during such fifteen minute period.

Moreover, in systems where the minute hands only of the secondary clocks are synchronized once an hour, usually from a master clock, to correct for minor gains or losses, if the power to the secondary clocks should be interrupted for over an hour, then even though the master clock should continue to deliver synchronization impulses, it would be necessary manually to reset all the secondary clocks upon resumption of the power in order to correct for the number of hours of error, with the attendant difficulties heretofore described.

20 It is among the objects of this invention to provide a control equipment which may be added to a conventional secondary clock system without necessitating changes in the circuit leads thereof or in the master or secondary clock construction, which will maintain the secondary clocks in time with the master clock during normal movement of the latter, which in the event of power failure, automatically will reset all the secondary clocks upon resumption of such power 30 regardless of the length of such failure, and in addition, will upon manual resetting of the master clock, automatically and expeditiously assure corresponding resetting of the secondary clocks regardless of whether such resetting is for a fraction of a minute or for many hours, said control equipment ensuring that at no time will manual access to the secondary clocks be required.

Another object is to attain the above objectives by resort to a simple self contained control transmission and circuit interconnecting the conventional master clock and a conventional secondary clock with their conventional connecting circuits, that is neat, compact and sturdy and relatively silent in operation, having but few moving parts that are easy to assemble and not likely to get out of order, thereby requiring but little maintenance, that does not require additional leads and connections, that does not consume more current than normally required to drive conventional secondary clock systems and which will reduce the cost of maintenance of the clock system.

Another object is to provide a control transmission and circuit which maintains the secondary clocks in correct timed relation with the master clock without interfering with the use of

the conventional remote controlled electric periodic synchronization of the master clock, which will cause all the secondary clocks in the system immediately to correct their setting after the master clock is synchronized and which will permit such periodic correction of the secondary clocks without impairing the operation of the master clock in governing the correct reading of the secondary clocks.

According to the invention, a control equipment is provided comprising a master clock, a secondary clock hereinafter designated a pilot clock, a control transmission mechanically interconnecting said clocks and a control circuit governed by said control transmission, which circuit effects operation both of said pilot clock and of the plurality of remote secondary clocks in the system.

The control transmission includes a pair of gear trains driven respectively by the master clock and pilot clock and a pair of differential switches controlled thereby and governing the circuit for actuating the pilot clock and the secondary clocks.

A transmission element displaced by the regular movement or by the manual setting of the master clock, as for instance by a knob on the minute arbor thereof, sets the differential switch into operative position and when the pilot clock has been advanced electrically and reaches conformity with the master clock, the differential switch will have been restored to inoperative position.

Preferably two differential switches are provided, one for the minute correction and one for the hour correction, and the switches are connected in parallel so that either may control the system.

In a preferred embodiment herein shown, the differential switches each comprise a pair of gears, each pair being idly mounted on a separate axis. Each pair of gears has a pair of contacts associated therewith which will close when the master clock and pilot clock do not indicate the same time, thereby to close a circuit to deliver impulses to the motors of the pilot clock and the secondary clocks and thus to advance them until they are in conformity with the master clock, at which time said differential switch contacts will reopen and the impulses to the pilot clock and secondary clocks will cease.

The master clock preferably is driven by an independent power supply such as a dry cell so as to operate independently of the main power supply which actuates the pilot clock and secondary clocks, thereby ensuring continued operation of the master clock in case of power failure.

In a preferred embodiment, a conventional remote controlled synchronizer is incorporated in the master clock periodically to correct its timing in accordance with timing signals from a remote source such as by wireless impulses from a control station. Also in the master clock is conventional mechanism to actuate the synchronizers in the secondary clocks, say 15 minutes after such setting of the master clock, thereby guarding against loss in time in the outermost secondary clocks that should fail to respond to all the short duration actuating impulses from the master clock.

Referring now to the drawings in which are shown one or more of various possible embodiments of the several features of the invention,

Fig. 1 is a fragmentary front elevational view of the control equipment with parts broken away,

Fig. 2 is a side elevational view of said equipment partly in cross section,

Fig. 3 is a sectional view on a larger scale taken along line 3—3 of Fig. 1,

5 Fig. 4 is a diagrammatic view of the control equipment including the control circuit, incorporated in a secondary clock system, and

Fig. 5 is a fragmentary view of another embodiment of the control circuit.

Referring now to the drawings, a conventional secondary clock system is provided comprising a plurality of secondary clocks S located in any suitable place on board a ship, train or plane. Illustratively the secondary clocks are each preferably driven in one-half minute steps by a reversing polarity impulse motor of the type fully described in my copending application Serial No. 696,591, filed September 12, 1946, now issued Patent No. 2,469,834, dated May 10, 1949.

A conventional master clock M is also provided, preferably having its own power supply (not shown) which may be a dry cell battery.

The master clock M and a secondary clock hereinafter designated as pilot clock P which together form part of the control equipment, are positioned on a control panel with the minute arbors 16 and 17 thereof respectively preferably vertically aligned, and extending laterally from said control panel.

30 Associated with the master clock M and the pilot clock P and interconnecting the two is the control transmission 10 which also forms part of the control equipment and which comprises a frame 11 mounted on the control panel over the master clock M and the pilot clock P and having a front panel 12 and a rear panel 13 affixed thereto in spaced relation by spacer bars 13'.

35 Mounted on the frame 11 between the front and rear panels 12 and 13 are two identical gear trains 14 and 15 provided with a twelve to one reduction ratio and driven respectively by the minute arbors 16 and 17 of the master clock M and the pilot clock P.

40 As the gear trains 14 and 15 are identical, only the former will be described in detail, corresponding parts of the latter having the same reference numerals primed.

45 Gear train 14 comprises an arbor 21 connected to minute arbor 16 of the master clock by coupling 23 and journaled at its rear end in a bearing opening 22 in rear panel 13. The front end of arbor 21 has an hour hand sleeve 24 idly mounted thereon and journaled in a bearing bushing 25 in front panel 12.

50 Affixed upon arbor 21 by set screw 32, near the rear end thereof between panels 12 and 13 is a gear 29 having a pinion 31 rigid therewith. Pinion 31 meshes with a gear 33 mounted on an arbor 34 journaled in bearing openings 35 and 36 in the front and rear panels 12 and 13 respectively. Rigid with gear 33 is a pinion 37 affixed to arbor 34 by set screw 38. Pinion 37 meshes with gear 39 which is affixed to sleeve 24, upon the reduced nose 41 at the forward end of which is affixed the hour hand 43.

55 Upon the reduced forward end 44 of arbor 21 protruding beyond sleeve 24 and clock face 42 is mounted a knurled knob 47 which is retained securely against shoulder 45 of the arbor 21 by nut 48 threaded on the extremity 46 of said arbor 21. Knob 47 has a minute hand 49 affixed thereto.

60 The reduced portion 44' of arbor 21' of gear train 15 is not as long as that of arbor 21 as no knob 47 is provided. Instead a collar 47'

is securely retained against shoulder 45' by nut 48' and carries minute hand 49'.

Associated with both the gear trains 14 and 15 are the differential switches 51 and 52 controlling the setting of the minute and hour hands respectively of the secondary clocks and of the pilot clock.

As the differential switches 51 and 52 are identical only the former will be described in detail, corresponding parts of the latter having the same reference numerals primed.

As clearly shown in Fig. 3, differential switch 51 comprises a stud 53 rigidly affixed to the rear panel 13 by a screw 54 and having two independently rotatable hubs 55 and 56 idly mounted thereon and comprising respectively identical gears 57 and 58 spaced from each other.

Gear 57 meshes with gear 29 of gear train 14 and is driven thereby in a counterclockwise direction and gear 58 meshes with gear 29' of gear train 15 and is also driven in a counterclockwise direction.

Gear 57' of differential switch 52 meshes with pinion 37 of gear train 14 and is driven thereby in a clockwise direction and gear 58' of differential switch 52 meshes with pinion 37' of gear train 15 and is also driven thereby in a clockwise direction.

It is therefore apparent that gears 57 and 58 of differential switch 51 are driven respectively by gears 29 and 29' which control the movement of the minute hands of the master and pilot clocks and gears 57' and 58' of differential switch 52 are driven, respectively, by pinions 37 and 37' which control the movement of the hour hands of the master and pilot clocks.

Gear 57 has a rivet 59 therethrough and rigid therewith, provided with a rounded head 61 on its inner face in juxtaposition to gear 58. The latter has a cam stud 62 with a rounded head 64 extending through an opening 63 therein and adapted to engage the head 61 of rivet 59 when the rivet and the stud are in registry.

The free end 65 of stud 62 is affixed to the end of a resilient contact arm 66 which is affixed at its free end in a mounting block 67 of insulating material secured to the face of gear 58 by screws 68, said contact arm 66 being insulated from said gear.

Also affixed in mounting block 67 between contact arm 66 and the gear 58, and in electrical contact with the latter, is a contact arm 69 carrying a contact 71 at one end in registry with a corresponding contact 72 on contact arm 66 and spaced therefrom when stud 62 is in engagement with rivet 59.

Also carried on mounting block 67 in contact with contact arm 66 is a resilient contact arm 73 carrying a contact 74 at one end thereof axially aligned with stud 53 and which is in engagement with a contact 75 carried by an arm 76 affixed to front panel 13 by screws 77, the two contacts 74 and 75 providing a rotating connection.

The master clock, pilot clock and control transmission above described have associated therewith a control circuit which includes a plurality of relays and associated elements to be herein-after described and which also forms part of the control equipment.

Control circuit

Contacts 71, 72 and 71', 72' of differential switches 51 and 52 respectively, are preferably connected in parallel as shown in Fig. 4. Thus contacts 71 and 71' are connected through fixed

contact arms 69 and 69' on gears 58 and 58', respectively, and the frame 11, the latter being connected from terminal 81 thereon to negative main N by leads 78' and 79. Contacts 72 and 72' are connected through contact arms 66 and 66', respectively, contact arms 73 and 73', respectively, contacts 74 and 74', respectively, contacts 75 and 75' respectively, arms 76, 76', respectively, and lead 82 connecting said arms 76 and 76'. Arm 76 is connected by lead 83 to one end of the coil 80 of the control relay R-1, the other end of which is connected by leads 84 and 85 to fuse 86 and thence by lead 87 to positive main P.

A time delay circuit is provided for relay R-1 comprising resistor 88 and condenser 89, connected in parallel thereacross by leads 91 and 92. This circuit functions to keep relay R-1 energized for the reason hereinafter set forth.

Relay R-1 which is of the single pole double throw type has a pair of fixed contacts 93 and 94 and a movable contact arm 95 connected at one end to the coil 80 by lead 84 and to positive main P through lead 85, fuse 86 and lead 87. Contact 93 is connected by lead 96 to the movable contact arm 97 of synchronization relay R-2 which is of the single pole single throw type, and also to one end of the coil 98 of relay R-2. The other end of the coil 98 is connected by lead 99 to one terminal 101 of the synchronization switch 102, the other terminal 103 of which is connected by leads 104 and 79 to negative main N.

Fixed contact 105 of relay R-2 is connected by lead 106 to one side of the coil 111 of the synchronization mechanism in each of the secondary clocks S of which three are illustratively shown. As such synchronization mechanism forms per se no part of this invention, it will not be described in detail, being diagrammatically represented by coil 111.

Fixed contact 94 of relay R-1 is connected by lead 112 to common contact 113 of impulse relay R-3 which is of the double pole double throw type, and thence by lead 114 to one side of variable resistor 115, the other side of which is connected by lead 116 to one end of coil 117 of relay R-3. The other end of coil 117 is connected to terminal 118 of an intermittent circuit interrupter 119, desirably of the thermal type, the other terminal 121 of which is connected by lead 122 and leads 123 and 124 to fixed contacts 125 and 126, respectively, of relay R-3, and by leads 127 and 79 to negative main N.

The circuit interrupter 119 which is conventional in construction and forms per se no part of this invention illustratively is of the type comprising a fixed contact arm 128 connected to terminal 118 and having a contact 129 at the end thereof in registry with a contact 131 at the end of movable contact arm 132, and normally in engagement therewith when no current is flowing through the interrupter 119. Movable contact arm 132 is pivoted as at 133 and a filament wire 134 is looped over the free end 135 thereof, the filament wire being of such length when not conducting and therefore cold, as to keep contacts 129 and 131 together. One end of the filament wire is connected by lead 136 to terminal 121 and the other end is connected by lead 137 to the movable contact arm 132. A coil spring 138 normally urging the contacts to open position assures rapid opening of the latter without arcing when the filament is heated.

It is of course to be understood that other types of circuit interrupters could be utilized herein, the one shown being merely illustrative.

The movable contact arms 139 and 140 of relay R-3 move in unison, are insulated from each other and are associated, respectively, with contacts 126, 113 and 113, 125. Contact arm 139 is connected by leads 141, 142 to one side of coil 148 of the secondary clock motors and by leads 141 and 147 to one side of coil 148' of the pilot clock motor.

Contact arm 140 is connected by leads 149 and 150 to the other side of coil 148 and by leads 149 and 154 to the other side of coil 148'.

The motors which have been diagrammatically represented by coils 148 and 148' are of the reversing polarity type requiring impulses for energization.

It is to be noted that lead 142 is common to both the synchronization coil 111 and the motor coil 148 in the secondary clocks.

Operation

Rotation of minute arbor 21 driven from arbor 16 of the master clock M rotates gear 29 and pinion 31 affixed thereon. Pinion 31 through gear 33 on arbor 34 rotates pinion 37 which through gear 39 drives sleeve 24 with hour hand 43 affixed thereon.

As gear 29 rotates in a clockwise direction, it rotates gear 57 in counterclockwise direction on stud 53 and with it rivet head 61, which moves out of engagement with the head 64 of stud 62. As rivet head 61 rides off stud 62, resilient arm 66 will move the latter inwardly into opening 63 in gear 58 to cause closure of normally open contacts 71 and 72.

It is to be noted that rivet head 61 does not have to move completely off stud 62 for contacts 71 and 72 to engage but even a slight movement of the rivet head down the curved head 64 of stud 62 is sufficient. Upon closure of contacts 71 and 72, a circuit will be completed to control relay R-1 from negative main N, leads 79 and 79', terminal 81, through the frame to fixed contact arm 69, contacts 71 and 72, movable contact arm 66, contact arm 73, contacts 74 and 75, arm 76, lead 83, through coil 80 of relay R-1, leads 84 and 85, fuse 86 and lead 87 to positive main P.

Energization of relay R-1 will move movable contact arm 95 into engagement with fixed contact 94, thereby completing a circuit to impulse relay R-3. The circuit is from positive main P, lead 87, fuse 86, lead 85, contact arm 95, contact 94, lead 112, common contact 113, lead 114, through variable resistor 115, lead 116, through the coil 117 of relay R-3 to terminal 118 of circuit interrupter 119, fixed contact arm 128, normally closed contacts 129 and 131, lead 131, filament 134, lead 136 to terminal 121, leads 122, 127 and 79 to negative main N.

Energization of relay R-3 will move movable contact arms 139 and 140 thereof into engagement with fixed contacts 113 and 125, respectively, thereby delivering an impulse to the coils 148 and 148' of the motors of the secondary clocks S and of the pilot clock P, respectively. The circuit is from positive main P, lead 87, fuse 86, lead 85, contact arm 95, contact 94, lead 112, contact 113, contact arm 139, leads 141 and 142, through coils 148 of secondary clocks S to lead 150 and in parallel therewith from lead 141 through lead 147 and the coil 148' of pilot clock P, to lead 154, said parallel circuit being completed by way of lead 149, through contact arm 140, fixed contact 125, leads 123, 127 and 79 to negative main N.

The impulse delivered to the coils 148 and 148' of the motors of the secondary clocks and pilot clock will cause the armature of their re-

5
spective motors to rotate one step which illustratively is 90 degrees, thereby rotating the minute arbor 17 of the pilot clock 19 and the corresponding arbors 151 of the various secondary clocks.

The gearing of the pilot clock and secondary clocks which are identical, for purposes of illustration will move the minute hands one-half minute at each impulse.

As the current flows through filament 134, it heats the latter causing it to expand, thereby enabling spring 138 to pivot arm 132, thus separating contacts 129 and 131 to break the circuit to the coil 117 of impulse relay R-3. Spring 150' thereof will thereupon move the arms 139 and 140 so that they respectively engage contacts 126 and 113. This will reverse the polarity of the current to the coils 148 and 148' of the secondary clock motors and the pilot clock motor and deliver another impulse thereto.

With contacts 129 and 131 of circuit interrupter 119 separated, no current will pass through filament 134 and it will cool and contract, bringing contacts 129 and 131 into engagement to again energize coil 117 of relay R-3 to cause an impulse again reversed in polarity to be delivered to coils 148 and 148'.

By varying the resistance 115, the amount of current flowing through the filament of circuit interrupter 119 can be controlled. The greater the current flow the shorter the period of time it will take the filament to heat up and hence the more rapid the rate of impulses delivered to the motors of the secondary clock S and the pilot clock P.

35
40
45
50
55
The circuit interrupter desirably has a frequency of from one to two times a second. The rate utilized depends upon the length of the lines and the number of secondary clocks in the system. Thus with long lines and many circuits, the voltage drop along the line may be such that if the impulses are rapidly transmitted, the individual impulses may not have sufficient force or long enough duration to actuate the more distant secondary clock motors. Thus the secondary clocks near the master clock would indicate the proper time while the more distant secondary clocks would be in error.

As arbor 21' rotates under the drive from arbor 17 of the pilot clock at each impulse thereto, it will rotate the minute hand 49' and the hour hand 43'. It will also rotate gear 29' and gear 58 in mesh therewith. This rotation of gear 58 will continue in intermittent steps with each impulse until stud 62 engages rivet 59 and rides up the rounded head 61 thereof sufficiently to cam movable contact arm 66 away from contact arm 69 to separate contacts 71 and 72 so that the circuit to the control relay R-1 will be broken and spring 95' thereof will move movable contact arm 95 into engagement with contact 93.

Thus during normal operation of the clock system after each small advance of the minute hand of the master clock, the minute hands of the pilot clock and the secondary clocks will also move a corresponding amount.

It is to be noted that although the hour hands of the pilot clock and the secondary clocks will also advance with each advance of their respective minute hands, this advance is so slight that rivet head 61' will not move sufficiently to cause stud 62' to be displaced enough to cause contacts 71' and 72' to engage. Therefore the circuit controlled by said contacts 71', 72' will not be closed during normal operation of the sys-

tem. However, as contacts 71, 72 and 71', 72' are in parallel, only one pair need close in order for the control circuit to be energized.

As the circuit to the relays and to the intermittent circuit interrupter 119 is broken except after each movement of the master clock, the current consumption of the system is a minimum.

As the contacts 71, 72 may separate quickly during the impulse due to the rapid movement of the pilot clock, thereby deenergizing relay R-1 and preventing a complete impulse from reaching the secondary clock motors which would prevent rotation of the latter, it is desirable that relay R-1 remain energized for a short interval after the circuit thereto has been broken. To this end, the time delay circuit comprising resistor 88 and condenser 89 is provided, the condenser becoming charged when coil 80 is initially energized, and discharging through the resistance and coil 80 when the circuit through contacts 71, 72 or 71', 72' is interrupted to keep the coil energized for a slight period of time thereafter. Thus, as contact arm 95 will remain against contact 94, the complete impulse from circuit interrupter 119 will be delivered to the pilot and secondary clock motors.

Illustratively on each hour, the synchronizer (not shown) in the master clock is energized from some remote source and the minute hand of the master clock will be moved exactly to the hour indication. At say exactly a quarter after the hour, synchronization switch 102 is closed by the synchronization mechanism (not shown). Inasmuch as rivet 61 and stud 62 are so positioned with respect to each other that contacts 71 and 72 will not engage until 15 seconds after a minute interval or 15 seconds before a minute interval, the control relay R-1 will not be energized at exactly the minute intervals and there will be no danger of the normal impulse and the synchronization impulse occurring at the same time. Thus, with synchronization switch 102 closed and relay R-1 deenergized, contact arm 95 of the latter will remain in engagement with fixed contact 93 to complete the circuit to synchronization relay R-2, the circuit being from positive main P, lead 87, fuse 86, lead 85, contact arm 95, contact 93, lead 96, coil 98 of relay R-2, lead 99, contacts 101 and 103 of synchronization switch 102, and leads 104 and 79 to negative main N. Movable contact 97 will move into engagement with fixed contact 105, thus completing a circuit from positive main P, lead 87, fuse 86, lead 85, contact arm 95, contact 93, lead 96, contact arm 97, contact 105, lead 106, through synchronization coil 111 through common lead 142, lead 141, contact arm 139, contact 126, leads 124, 127 and 79 to negative main N. Thus all the secondary clocks will be synchronized.

Up to this point the operation has been described with respect to the normal driving and synchronizing function of the system. If it is desired to advance all the clocks in the system one hour, as would be necessary for example in a ship traveling from west to east every time it crossed a time zone, it is merely necessary to turn knob 48 of the master clock arbor 21 so that the hands thereof are advanced one hour. As arbor 21 is connected to arbor 16 of the master clock and the latter is connected to the gear train (not shown) in the master clock by a conventional friction clutch (not shown), the gear movement in the master clock will not be affected.

Rotation of the clock hands one hour will re-

store the minute hand to its original position with rivet 61 and stud 62 in engagement and contacts 71, 72 separated. However, the hour hand will have been advanced and gear 39 will have rotated pinion 37, which in turn rotated gear 57' in a clockwise direction, causing rivet 61' to move away from stud 62' permitting the latter to move into the opening in gear 58' to bring contacts 71' and 72' into engagement as previously described with respect to contacts 71 and 72.

Closing of contacts 71' and 72' which are connected in parallel with contacts 71 and 72 will complete the circuit to the control relay R-1 previously described, thereby delivering impulses to the motors of the pilot clock and secondary clocks to rotate the same. As it requires two impulses to the pilot clock and secondary clock motors to rotate the hands thereof one minute, it will take 120 impulses to advance the hands one hour and as the impulses are occurring at from one to two times a second, it will take from one to two minutes to set the clocks ahead one hour.

Since by the arrangement above described, the synchronizer circuit is inactive whenever the differential switches or either of them is in operative position with the contacts thereof closed, there can be no interference with or delay in the return of the differential switches to inoperative position. Thus, in the absence of such arrangement, if the master clock should be advanced one hour, it would require 120 impulses to bring the secondary clocks in time therewith. If the minute hand should have advanced to say the 35 minute mark and a synchronization impulse should occur, the minute hands would be brought back to say the 15 minute mark and it would require 40 more impulses to restore the minute hand to its original position, thereby slowing up the resetting operation. By reason of the interlocking feature of control relay R-1, this difficulty is avoided. The synchronization impulse can only reach the secondary clocks when relay R-1 is deenergized and as the relay R-1 will remain energized during the entire resetting period, no synchronization impulse will be delivered at such time.

Inasmuch as the pilot clock is in close juxtaposition to its source of power, which is controlled by the circuit interrupter, there is little or no danger of line losses which might interfere with the proper functioning of the pilot clock, and hence the latter will always be in time except in the case of power failure, and no synchronizer is required therefor, although one may be so provided if desired.

Although in the embodiment herein chosen to illustrate my invention, a reversing polarity impulse motor is utilized in both the pilot clock and secondary clocks, it is within the scope of this invention from its broader aspects to utilize impulse motors that are not of the reversing polarity type or to utilize alternating current motors or direct current motors not of the impulse type.

In Fig. 5, the circuit of Fig. 4 is shown modified to adapt it for use with an impulse motor not of the reversing polarity type. To this end the lead 123 need only be removed. Thus as soon as relay R-1 is energized as heretofore described, an impulse will be delivered to the motors of the pilot clock and the secondary clocks, the circuit as shown in Fig. 5 being from positive main P, lead 87, fuse 86, lead 85, contact arm 95, contact 94, lead 112, contact 113, contact arm 140, lead 149 and leads 150 and 154 to one side of the pilot

clock motor, and through leads 142 and 147 from the other side of the motors, lead 141, contact arm 139, contact 126 and leads 124, 127 and 79 to negative main N.

The energization of relay R-1 will also complete a circuit to circuit interrupter 119 from positive main P, lead 87, fuse 86, lead 85, contact arm 95, contact 94, lead 112, contact 113, lead 114, variable resistor 115, lead 116, coil 117 of relay R-3 to terminal 118 of the circuit interrupter 119 and then from terminal 121 thereof, leads 122, 127 and 79 to negative main N.

Thus relay R-3 will be energized, moving contact arms 139 and 140 thereof away from contacts 126 and 113, respectively. As contact arm 140 will be in engagement with dead contact 125, the circuit to the motors will be broken.

It is apparent therefore that with each make and break of the circuit interrupter, one impulse will be delivered to actuate the pilot clock and secondary clock motors.

That this modified system shown in Fig. 5 could be utilized to control alternating current or direct current motors in the pilot and secondary clocks is readily apparent. The making and breaking of the circuit thereto as above described would intermittently energize such motors to advance the hands of the clocks.

As many changes could be made in the above construction, and many apparently widely different embodiments of this invention could be made without departing from the scope of the claims, it is intended that all matter contained in the above description or shown in the accompanying drawings shall be interpreted as illustrative and not in a limiting sense.

Having thus described my invention what I claim as new and desire to secure by Letters Patent of the United States is:

1. A control equipment for a secondary clock system of the type comprising a master clock, a plurality of secondary clocks and a pilot clock, said secondary clocks and said pilot clock each having an impulse motor; said equipment comprising a control transmission mechanically interconnecting said master clock and said pilot clock, said transmission comprising a pair of spaced parallel gears idly mounted on a common axle, said gears being driven by said master clock and said pilot clock respectively, a member fixed on one of said gears and protruding from the inner face thereof, a movable member extending through the other of said gears and adapted to engage said fixed member when in registry therewith, a resilient arm having a contact thereon and carrying said movable member, and affixed to and insulated from said last named gear, a contact arm affixed to said last named gear and having a contact thereon in registry with the contact on said movable contact arm and normally spaced therefrom when said movable member and said fixed member are in engagement, said contact and said movable contact arm defining a switch, a circuit interrupter controlled by said switch and connected in circuit with said impulse motors, whereby when said movable member and said fixed member are moved out of engagement by movement of the gears of said pair of gears driven by said master clock, the switch will close to engage said circuit interrupter, for impulsing said impulse motors to move said pilot clock and secondary clocks into synchronization with said master clock.

2. A control equipment for a secondary clock

75

system, said equipment comprising a frame, a gear train mounted on said frame, driving means for said gear train, a second gear train mounted on said frame having the same gear ratio as said first gear train, driving means for said second gear train, each of said gear trains comprising a first arbor, a gear and pinion affixed on said first arbor, a second arbor and a gear and pinion affixed on said second arbor, said last named gear meshing with said pinion on said first arbor, thereby rotating said pinion on said second arbor, a sleeve idly mounted on said first arbor, a gear rigid with said sleeve and meshing with the pinion on said second arbor, thereby rotating said sleeve, indicating hand affixed to said first arbor and said sleeve respectively, and rotated thereby, a pair of switches mounted on said frame, each of said switches comprising a pair of movable members, one of the movable members of each of said switches meshing respectively with the gear on said first arbor of each of said gear trains and the other movable member of each of said switches meshing respectively with the pinion on said second arbor of each of said gear trains, and circuit means controlled by said switches to actuate said second driving means.

3. A control equipment for a secondary clock system, said equipment comprising a frame, a gear train mounted on said frame, driving means for said gear train, a second gear train mounted on said frame having the same gear ratio as said first gear train, driving means for said second gear train, each of said gear trains comprising a first arbor, a gear and pinion affixed on said first arbor, a second arbor, a gear and pinion affixed on said second arbor, said last named gear meshing with said pinion on said first arbor, thereby rotating said pinion on said second arbor, a sleeve idly mounted on said first arbor, a gear rigid with said sleeve and meshing with the pinion on said second arbor thereby rotating said sleeve, indicating hands affixed to said first arbor and said sleeve respectively, and rotated thereby, a pair of switches mounted on said frame, each of said switches comprising a pair of spaced, parallel gears, an axle affixed to said frame and idly mounting said parallel gears so that they are movable with respect to each other, a member fixed on one of said gears protruding from the inner face thereof, a movable member extending through the other of said gears and adapted to engage said fixed member when in registry therewith, a resilient arm having a contact thereon and carrying said movable member and affixed to and insulated from the other of said gears, a contact arm affixed to said last named gear and having a contact thereon in registry with the contact on said movable contact arm and normally spaced therefrom when said movable member and said fixed member are in engagement, one of the gears of each of said switches meshing respectively with the gear on said first arbor of each of said gear trains, and the other of said gears of each of said switches meshing respectively with the pinion on said second arbor of each of said gear trains, and circuit means controlled by said switches to actuate said second driving means.

4. A clock system comprising a master clock, a pilot clock having an impulse motor, a plurality of secondary clocks each having an impulse motor, normally open switch means controlled by said master clock and said pilot clock respectively, a control relay in series with said

switch means and actuated thereby when said switch means are closed, said control relay having a pair of normally open contacts, an impulse relay, an intermittent circuit breaker in series with said impulse relay and said pair of normally open contacts, said impulse relay being connected to deliver impulses of reverse polarity upon intermittent energization thereof, whereby when the closing of the switch of the master clock energizes said control relay to close its contacts, said impulse relay and said circuit breaker will be energized for intermittent energization of said impulse relay to deliver a plurality of impulses to said pilot clock and said secondary clock to actuate the latter.

5. The combination set forth in claim 4 in which said impulse relay is of the double pole double throw type connected to deliver impulses of reverse polarity at each position.

HENRY MAERZ.
